UNITED STATES PATENT OFFICE.

ANDREW A. AHLQUIST, OF SOUTH EASTON, MASSACHUSETTS, ASSIGNOR TO UNITED SHOE MACHINERY COMPANY, OF PATERSON, NEW JERSEY, A CORPORATION OF NEW JERSEY.

CHANNELING-MACHINE.

SPECIFICATION forming part of Letters Patent No. 788,809, dated May 2, 1905.

Application filed May 5, 1902. Renewed July 30, 1904. Serial No. 218,807.

To all whom it may concern:

Be it known that I, ANDREW A. AHLQUIST, a citizen of the United States, residing at South Easton, in the county of Bristol and State 5 of Massachusetts, have invented certain new and useful Improvements in Channeling-Machines; and I do hereby declare the following to be a full, clear, and exact description of the invention, such as will enable others skilled in 10 the art to which it appertains to make and use the same.

The present invention relates to channeling-machines for channeling the soles of boots and shoes. Such machines comprise a channeling-knife which makes an incision in the sole to form a channel and a channel flap or lip, which is subsequently turned up in order to open the channel for the reception of the stitches or other fastening devices by which 15 the sole is secured to the other portions of the shoe. The operation of turning up the lip is usually performed upon a separate machine, although machines have been devised which are designed to channel the sole and turn up 20 the lip at one operation. As I am advised as to the state of the art, channeling-machines which are adapted to turn up the channel flap or lip have been provided with a stationary 25 lip-turning device or with a lip-turning device 30 vice arranged to vibrate transversely to the line of feed.

The object of the present invention is to provide a lip-turning device of improved construction, arrangement, and mode of operation 35 particularly adapted for use in a channeling-machine whereby the sole of a shoe can be channeled and the lip turned up at one operation in a satisfactory manner, but which is also adapted for use in a machine which merely 40 acts to turn up the lip.

With this object in view my invention contemplates providing a lip-turning device arranged to remain in contact with the lip of a shoe-sole and shaped to turn up the lip and 45 means for vibrating the lip-turning device longitudinally of the lip or in the line of feed. By so vibrating the lip-turning device it is caused to move intermittently over the lip

while in contact therewith and acts to turn over the lip and set it in position in a certain 50 and reliable manner. On account of the intermittent action of the lip-turning device less power is required to run the machine in which it is used than when a stationary lip-turning device is used, and the lip-turning device can 55 be incorporated in a sole-channeling machine without appreciably increasing the power required to run the machine.

My improved lip-turning device is preferably embodied in a channeling-machine provided with a channeling-knife which is also vibrated in the line of feed and when embodied in such a machine is preferably attached to the movable part of the machine which carries the channeling-knife, so that the same mechanism 65 is utilized to actuate both the channeling-knife and the lip-turning device.

My invention is intended, primarily, as an improvement on a class of channeling-machines well known in the art, an example of 70 which is disclosed in the patent to W. C. Meyer and Z. T. French, No. 630,339, dated August 8, 1899, and in the drawings accompanying this application I have illustrated my invention embodied in a machine similar to that 75 disclosed in said patent. While, however, my invention is particularly applicable to such machine and when embodied therein possesses advantages in construction and operation which will be obvious to those skilled in the 80 art, it is to be understood that it is not limited to such machine, but may be embodied in many different constructions without departing from the spirit thereof.

Referring to the drawings, Figure 1 is a 85 view in side elevation of a rough-rounding and channeling machine similar to the machine disclosed in Patent No. 630,339, above referred to, with my invention applied thereto. Fig. 2 is a detail sectional view taken on the line 90 2-2 of Fig. 3, illustrating a portion of the knife-carrier with a channeling-knife and lip-turning device secured thereto. Fig. 3 is a plan view of the parts illustrated in Fig. 2. Fig. 4 is a view in front elevation of the parts 95 illustrated in Fig. 2, the sole-support being

omitted. Figs. 5, 6, and 7 are views in plan, front elevation, and side elevation of a portion of the carrier and of a channeling-knife and lip-turning device secured thereto, illustrating a modified form of my invention; and Fig. 8 is a detail view, in side elevation, looking in the opposite direction from Fig. 1, illustrating the action of the channeling-knife and lip-turning device in cutting the channel 10 and turning up the lip.

In the drawings, 1 indicates the frame of the machine, 2 the cam-shaft journaled therein, 3 the oscillating arm pivoted at the rear of the machine-frame and extending beneath the cam-shaft 2 to the front of the machine, 4 the vertically-movable block mounted in the forward end of the horizontally-movable slide 5, mounted on the oscillating arm 3, 6 the plate secured to the block 4, 7 the stud projecting downwardly from the plate 6 and secured at its lower end in a lug projecting from the block 4, and 8 the sole-support rotatably mounted upon the stud 7, said parts and all other parts illustrated in the drawings and not hereinafter otherwise specifically described being the same as the corresponding parts of the machine illustrated in the patent above referred to, to which reference is made for a description of their construction, arrangement, and mode of operation.

Referring to Figs. 2, 3, and 4, the channeling-knife is indicated at 9, the shank of the knife being arranged horizontally and the edge of the knife extending diagonally 35 from the shank portion beyond the face of the work-support 8. The channeling-knife is secured above the work-support 8 to the plate 6 and stud 7 by means of a clamping-block 10, which is received in a slot cut in one side of 40 the upper end of the stud 7 and which is actuated by means of a clamping-screw 11, passing through the stud 7 and screwing into the block. The clamping-block is provided with an upwardly-projecting portion which forms 45 a shoulder, between which and the edge of the plate 6 the shank of the knife is clamped, the plate 6 being provided with a notch to receive the shank of the knife and the upwardly-projecting portion of the clamping-block.

50 During the operation of the machine the arm 3 is oscillated, as is clearly described in the patent above referred to, and the channeling-knife is vibrated in the line of feed. In the form of my invention illustrated in Figs. 55 2, 3, and 4 the lip-turning device is indicated at 12, and in order to cause it to vibrate in the line of feed it is secured, by means of a screw 13, to the clamping-block 10, as is clearly indicated in Figs. 3 and 4. As shown in these figures, the lip-turning device consists of a block 60 or plate which extends forward in front of the clamping-block and toward the channeling-knife and is provided at its forward upper edge with a projection or horn 14, which is received 65 in a notch formed in the rear portion of the

knife, so that the lip-turning device is located in close proximity to the knife. Below the horn 14 the forward end and the outer surface of the lip-turning device are shaped to engage the lip formed by the channeling-knife and turn it 70 over and press it against the sole, as is indicated in Fig. 8. It will be seen that the lip-turning device is located in close proximity to the channeling-knife and follows the knife and that by being secured to the same carrier 75 as the knife vibrates therewith and is thereby caused to move intermittently along the lip while remaining in engagement therewith. The lip-turning device thus acts to turn up the 80 lip and set it in position in a reliable and satisfactory manner as soon as it is formed by the channeling-knife. In actual practice it has been found that the addition of the lip-turning device does not appreciably increase 85 the power required to run the machine, and the machine is as satisfactory in operation as when used simply to channel the sole.

The cutting edge of the channeling-knife (illustrated in Figs. 2, 3, and 4) extends obliquely to the surface of the sole.

In Figs. 5, 6, and 7 I have illustrated a modified form of lip-turning device in connection with a channeling-knife the cutting edge of which is arranged more nearly parallel with the surface of the sole. Referring to these figures, 15 indicates the channeling-knife, and 16 the lip-turning device. The shanks of the channeling-knife and of the lip-turning device are both clamped between the upwardly-extending portion of the clamping-block 10 and the edge of plate 6 and are interlocked by means of a projection on one side of the shank of the channeling-knife and a corresponding slot in the adjacent side of the shank of the lip-turning device. The forward end of the lip-turning device extends downwardly from its shank in close proximity to the rear edge of the blade of the channeling-knife and is provided with a curved surface, practically forming a continuation of the inner surface of the blade of the channeling-knife, which acts to turn over the lip and press it against the sole. The shape of this surface and the manner in which the lip is turned over and pressed against the sole will be obvious from an inspection of Figs. 6 and 7 without further description.

Having thus indicated the nature and scope of my invention and having specifically described a machine embodying a preferred form thereof, I claim as new and desire to secure by Letters Patent of the United States—

1. A channeling-machine, having, in combination, a channeling-knife, a lip-turning device vibrating in the line of feed, and means for actuating the lip-turning device, substantially as described.

2. A channeling-machine, having, in combination, a channeling-knife vibrating in the line of feed, a lip-turning device vibrating in

the line of feed following the knife to turn over the lip formed thereby and means for actuating the knife and lip-turning device, substantially as described.

5 3. A channeling-machine, having, in combination, a channeling-knife vibrating in the line of feed, means for actuating the knife and a lip-turning device in close proximity to and movable with the vibrating channeling-knife, substantially as described.

10 4. A channeling-machine, having, in combination, a lip-turning device vibrating in the line of feed shaped to turn over the lip and press it against the sole, and means for actuating the lip-turning device, substantially as described.

15 5. A channeling-machine, having, in combination, a carrier, a channeling-knife and a lip-turning device secured to the carrier, and means for actuating the carrier to vibrate the

knife and lip-turning device in the line of feed, substantially as described.

6. The combination with means for supporting and feeding a shoe of a lip-turning device arranged to remain in contact with the lip, ²⁵ and means for vibrating the lip-turning device in the line of feed, substantially as described.

7. The combination with a lip-turning device arranged to remain in contact with the ³⁰ lip of a shoe-sole of means for vibrating the lip-turning device longitudinally of the lip, substantially as described.

In testimony whereof I affix my signature in presence of two witnesses.

ANDREW A. AHLQUIST.
